DANIEL L. JONES AND GEORGE T. JONES, OF PHILADELPHIA,
PENNSYLVANIA.

Letters Patent No. 86,078, dated January 19, 1869.

IMPROVEMENT IN MACHINE FOR BURRING WOOL

The Schedule referred to in these Letters Patent and making part of the same.

To all whom it may concern:

Be it known that we, DANIEL L. JONES and GEORGE T. JONES, of Philadelphia, Pennsylvania, have invented an Improvement in Wool-Burring-Machines; and we do hereby declare the following to be a full, clear, and exact description of the same.

Our invention consists of the combination and arrangement of a certain shield, and the drawing, burring, and slatted rollers of a wool-burring-machine, as fully described hereafter, so as to facilitate the passage of the dirt and knots from the wool, while the escape of the shorter fibres from the burring-roller is prevented.

In order to enable others skilled in the art to make and use our invention, we will now proceed to describe its construction and operation, reference being had to the accompanying drawing, which forms a part of this specification, and in which—

Figure 1 is a sectional elevation of our improved wool-burring-machine;

Figure 2, a plan view; and

Figure 3, a detached view, partly in section.

A is the frame of the machine;

B, the card-cylinder;

a' parallel rollers, between which the wool is drawn to the burring-roller C; and

b is a slatted roller, which revolves directly beneath, and with its blades or ribs almost in contact with the burring-roller C.

Inasmuch as the parts above referred to are well known to those familiar with this class of machinery, a more minute description of the same will be unnecessary.

At one side of the roller C, and between the rollers a' and b, is a shield, e, which is curved to correspond to the roller C, with the face of which it is almost in contact, while the rear edge of the plate is in such a

position that the blades of the roller b pass almost in contact with it.

As the wool is carried downward by the roller C, it passes over the shield e, which effectually prevents the escape of loose fibres, while the dust and smaller particles of dirt in the wool slide down the plate, and fall over its edge.

As the wool passes from contact with the plate, the burrs and knots protrude, and are struck by the slats or ribs of the roller b, and thrown to one side in the ordinary manner, the wool passing from the burring-roller to the card-cylinder B.

The slatted roller b, rotating so that the edges of its slats shall pass nearly in contact with the edge of the plate e, insures the separation of all burrs or knots from the wool, without disengaging any portion of the fleece from the burring-roller, the plate e, in fact, retaining the fleece in contact with the roller, and only permitting its knots or burrs to project from the face at a point where they may be struck by the slatted roller b.

The shield e may be perforated, or a series of small parallel rollers or slats, which will allow the dust to pass between them, without permitting the fibres to escape from the roller C, may be substituted for the shield.

We claim as our invention, and desire to secure by Letters Patent—

The combination and arrangement of the shield e, and drawing, burring, and slatted rollers, as and for the purpose described.

In testimony whereof, we have signed our names to this specification, in the presence of two subscribing witnesses.

DANIEL L. JONES.

GEORGE T. JONES.
